DESIGN FOR A HEATER

Bertrand B. Kahn, Cincinnati, Ohio, assignor to
The Estate Stove Company, Hamilton, Ohio, a
corporation of Ohio

Application November 18, 1933, Serial No. 49,789

Term of patent 7 years

To all whom it may concern:

Be it known that I, BERTRAND B. KAHN, a citizen of the United States of America, residing at Cincinnati, in the county of Hamilton, State of Ohio, have invented a new, original, and ornamental Design for Heaters, of which the following is a specification, reference being had to the accompanying drawing, forming part thereof.

Fig. 1 is a perspective view of the heater showing my new design;

Fig. 2 is a diagrammatic front elevational view on a reduced scale; and

Fig. 3 is a diagrammatic side elevational view on a reduced scale thereof.

The design comprises a casing which is rectangular in cross-section, the top of which comprises curved surfaces of contour blended with the body portion, the metal surfaces being preferably finished in vitreous enamel.

What is claimed is:

The ornamental design for a heater substantially as shown and described.

BERTRAND B. KAHN.
